Primary Examiner — Sheryl Lane

(74) Attorney, Agent, or Firm — Olive Law Group, PLLC

(57) **CLAIM**

The ornamental design for a stake, as shown and described.

DESCRIPTION

FIG. 1 is a top, front and right side perspective view of a first embodiment of a stake, showing my new design;

FIG. 2 is a bottom, rear and left side perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is an enlarged top plan view thereof;

FIG. 8 is an enlarged bottom plan view thereof;

FIG. 9 is a top and front perspective view of a second embodiment of the stake;

FIG. 10 is a bottom and rear perspective view thereof;

FIG. 11 is a top and front perspective view of a third embodiment of the stake;

FIG. 12 is a bottom and rear perspective view thereof;

FIG. 13 is a top and front perspective view of a fourth embodiment of the stake;

FIG. 14 is a bottom and rear perspective view thereof;

FIG. 15 is a top and front perspective view of a fifth embodiment of the stake; and,

FIG. 16 is a bottom and rear perspective view thereof.

The evenly dashed broken lines illustrate portions of the stake and form no part of the claimed design.

1 Claim, 16 Drawing Sheets
